By *Charles W. Jr.* Atty.

UNITED STATES PATENT OFFICE.

CHESTER M. ANGELL, OF CHICAGO, ILLINOIS, ASSIGNOR TO VESTA BATTERY CORPORATION, A CORPORATION OF ILLINOIS.

CLAMP FOR LEAD MOLDS.

Application filed November 25, 1921. Serial No. 517,447.

To all whom it may concern:

Be it known that I, CHESTER M. ANGELL, a citizen of the United States, and a resident of the city of Chicago, in the county of Cook and State of Illinois, have invented certain new and useful Improvements in a Clamp for Lead Molds; and I do hereby declare that the following is a full, clear, and exact description of the same, reference 10 being had to the accompanying drawings, and to the numerals of reference marked thereon, which form a part of this specification.

In casting articles of lead it is desirable 15 to take advantage of the fact that molten lead cools very rapidly and therefore the mold should be made to be opened or closed very quickly.

It is an object of this invention to devise 20 a fastening for a mold which shall be capable of being moved very quickly to the release position and yet shall securely hold the parts of the mold together when in fastening position.

25 It is a further object of this invention to provide a mold with two halves and a fastening device on one of these halves provided with a handle which by one continuous motion can be brought from a position 30 in which the halves are clamped together to a position in which they are completely free, so that one may be moved away from the other.

Other and further important objects of 35 this invention will be apparent from the disclosures in the specification and the accompanying drawings.

The invention (in a preferred form) is 40 illustrated in the drawings and hereinafter more fully described.

On the drawings:

Figure 1 is a front elevation of the mold.

Figure 2 is a top plan view.

Figure 3 is an end view.

45 Figure 4 is an end view showing the other end.

Figure 5 is a section upon the line 5—5 of Figure 1.

50 Figure 6 is a section upon the line 6—6 of Figure 1.

Figure 7 is a section upon the line 7—7 of Figure 1.

Figure 8 is a front view of one half of the mold with the other half removed.

As shown on the drawings:

The mold consists of two halves 1, 2, each provided with a handle 3. One of these halves is provided with dowel pins and the other with dowel holes, as indicated at 4 in Fig. 8, in order that they may be readily 60 and accurately positioned against one another. The half 1 is provided with a pair of ears 5 and 6, one of which, 5, has a slot the mouth of which is downward as shown at 7. The other ear has a slot opening upward, as shown at 8.

The other half 2 of the mold has pivoted at the center of its front or outside face a stirrup-shaped casting 9 shown in Figures 1 and 5. A pivot 10 for this casting affords 70 a swivel connection with the half 2. The casting is provided with a deep notch or saddle 11 which serves to seat a bar 12 which extends the length of the mold. Where the bar passes through the saddle 11 75 it is provided with a groove 13, and the up-standing portions of the saddle are crossed by a pin 14 which co-operates with the groove 13 to position the bar 12 and yet permit rotation thereof. The pin 14 is secured 80 in the casting 9 in any desired way. As illustrated in Figure 5, this may be done by upsetting the two ends of the pin.

The motion of the bar 12 corresponding to the swivelling movement of the casting 9 is 85 limited by a pin or stud 15, projecting from the front of the half 2 and preferably located near one corner thereof. The motion of rotation of the bar 12 about its own axis permitted by the saddle 11 and the groove 90 13 is limited by a lug 16, most clearly shown in Figure 6. This lug is of a generally square cross-section, as shown in Figure 6, but has one corner rounded as shown at 17. It is secured to the bar 12 at any desired 95 point along the length thereof and is held in place by means of a set screw 18. One end of the bar 12 is provided with a handle 19 which is at right angles to the bar.

A pair of plates 20 are secured, one near 100 each end of the half 2, and the ends of the bar 12 co-operate with these plates, as shown in Figure 7. For this co-operation the bar is cut away to provide an eccentric portion, as shown at 21, and when the bar is 105 rotated about its axis the change from the cut away side to a side of full radius, drives the plate 20, and so the half 2, toward the

- other half 1. Motion of the bar away from the half 1 during this turning is prevented by the seating of the ends of the bar in the slots 7 and 8 of the ears 5 and 6.
- 5 The upper edges of the inner faces of the two halves 1 and 2 are beveled for a portion of their length, as shown at 22 and 23. This affords, between the two beveled portions, an opening 24 by which the lead enters the 10 interior of the mold.

The operation is as follows:

Assuming the parts to be in the position indicated in full lines in Figure 1, lead is poured in through the opening 24, the beveled surfaces 22 and 23 serving as a funnel to guide the lead to the interior of the mold. Preferably this is done with the mold being one of a series of molds in a machine, so that the pouring is automatically 15 performed. As soon as the lead has had time to harden the mold is opened and the casting removed.

For this opening the handle 19 is grasped and moved downward from the full line position shown in Figure 1 and at the same time given a quarter turn so that the parts arrive at the position illustrated in dotted lines in Figure 1. The half 2 may then be removed from the half 1 by taking it from 20 between the projecting ears 20 and the casting may then be lifted out. To close the mold for the next casting operation, half 2 is again placed between the ears 5 and 6 and moved toward the half 1 so that the dowel 25 pins enter the dowel holes. The handle 19 is then grasped and moved upward until the ends of the bars 12 enter the slots 7 and 8. The bottoms of these slots serve as a stop to quickly and certainly position the bar in 30 this movement. The handle 19 is then moved further by rotating the bar 12. The lug 16 serves as a stop for this movement. During this movement the cut away eccentric portions 21 of the bar are rotated away 35 from the plates 20 and the higher or rounded surfaces of the bar coming against these plates thrust the member 2 home against the member 1 so that the mold is tightly closed.

60 It will be noted that the motion of the handle 19 is in one continuous direction during the closing operation so that the workman does not consciously change from

the swiveling movement about the pivot 10 to the rotating movement about the axis 55 of the bar 12; but with one motion of his hand combines the two movements, being unconscious of the change from one to the other, each movement being guided by the step for that movement. The same is true 60 of the motion made by the workmen during the opening of the mold, although the movements take place in reverse order.

I am aware that numerous details of construction may be varied through a wide 65 range without departing from the principles of this invention, and I therefore do not purpose limiting the patent granted otherwise than necessitated by the prior art.

I claim as my invention:

1. A mold, a casting swivelled upon said mold, a bar rotatably mounted in said casting, and stops for limiting the motion of the bar about said swivel and for limiting the motion of the bar about its axis.

70 2. In a mold, two halves, a pair of ears upon one of said halves, each ear having a slot therein, the mouths of the slots facing in opposite directions, a bar, a casting swivelled upon the other of said halves and having said bar rotatably mounted therein, whereby motion of the casting about its swivel will cause the two ends of the bar to enter the two slots in said ears simultaneously, cam surfaces upon the bar at each 75 end thereof, plates upon the second mentioned half adapted to co-operate with said cam surfaces, and means for rotating the bar about its axis whereby the cam surfaces will act against said plates to cause said 80 halves to move toward one another.

85 3. In a mold, two halves, means for locking said halves together, means for forcing said halves into contact, an operating member common to said two means and a handle 90 for said operating member whereby continuous motion of the handle in one general direction will both lock said halves and move them into contact.

95 In testimony whereof I have hereunto 100 subscribed my name in the presence of two subscribing witnesses.

CHESTER M. ANGELL.
